(57) **CLAIM**

The ornamental design for an x-ray sleeve for mattress cover for medical bed as shown and described.

DESCRIPTION

FIG. 1 is an environmental front perspective view of an x-ray sleeve for mattress cover for medical bed.

FIG. 2 is a front perspective view of the x-ray sleeve shown in FIG. 1.

FIG. 3 is a front view of the x-ray sleeve shown in FIG. 1.

FIG. 4 is a rear view of the x-ray sleeve shown in FIG. 1.

FIG. 5 is a top plan view of the x-ray sleeve shown in FIG. 1, with a bottom plan view being a mirror image thereof; and,

FIG. 6 is a right side elevational view of the x-ray sleeve shown in FIG. 1, with a left side elevational view being a mirror image thereof.

The broken lines shown in the drawings illustrate portions of the x-ray sleeve for mattress cover for medical bed that forms no part of the claimed design. The broken line truncations show symbolic breaks, and any portion of the x-ray sleeve for mattress cover for medical bed between the breakaways form no part of the claimed design. The broken lines in FIG. 1 showing mattress cover depict environment that also forms no part of the claimed design.
